SALVAGE APPARATUS

Eugene J. Romano, Seattle, Wash.

Application October 12, 1931. Serial No. 568,374

3 Claims. (Cl. 114—53)

My invention relates to salvage operations, and more especially to apparatus intended for attachment to, and thereafter the lifting of, sunken vessels.

5 Among the objects of my present invention are:

To facilitate the application of lifting lines depending from a submersible buoy to a sunken vessel;

10 To distribute the lifting effort from each such buoy over different parts of the vessel, and to cause individual lifting efforts to overlap;

To permit disconnection of the control and indicating apparatus on the salvage vessel without disconnection of lines to the buoys, whereby in 15 case of rough weather approaching, this apparatus may be thrown overboard to float until the weather enables the resumption of operations;

To indicate to the attendant upon the salvage vessel the depth of water—that is, the level of the 20 water within each buoy—so that it may be determined what proportion of its total lifting effort is being exerted at any given time;

25 To provide means enabling the employment of buoys with reduced dependent necks, as disclosed in a copending application filed herewith, especially when such buoys are brought close along side the sunken vessel.

30 My invention comprises the novel salvage apparatus, and the novel arrangement of parts therein, as shown in the accompanying drawings, described in the specification, and as will be more particularly pointed out by the claims which terminate the same.

In the accompanying drawings I have shown 35 my invention in forms now preferred by me.

Figure 1 is a general elevation of a salvage operation, showing buoys attached to a sunken vessel, and ready to raise the same.

Figure 2 is a perspective view of a detail, showing 40 the manner of attaching the lifting lines to the vessel to be raised.

Figure 3 is a view looking aft of a vessel with buoys attached thereto, according to one plan.

Figure 4 is a view similar to Figure 3, and Figure 5 is a bottom plan view, showing buoys attached according to a plan different from that 45 illustrated in Figure 3.

Figure 6 is an elevation of the essential control apparatus disconnectable from the salvage vessel, and Figure 7 is an end view thereof.

Figure 8 is an elevation, with parts broken away, of a buoy.

Figure 9 is an electrical diagram of the connections whereby the water level in each buoy is indicated.

In general, the operation contemplates the attachment to a vessel V to be raised, of a series of buoys generally designated by the numeral 2 and illustrated by way of example in Figure 1 as the buoys 21, 22, 23, 24, 25, 26 and 27. I prefer 60 that each of these buoys have a depending normally open neck 28, and rings 29, to which lifting lines 3 are attached. Preferably at least four such lifting lines depend from each buoy, and these are intended to be secured by suitable means, 65 such as the hooks 30, to the vessel V at separated points. Thus, as is shown in Figure 2, the hooks are engaged in port holes P of the vessel V, and in order that they may be attached with a minimum of effort, and without the necessity of a diver going 70 to a spot immediately beneath the buoy to secure a line, then to carry it off at a distance and attach it, which operations obviously will be difficult under water, with little light to aid, and in spots where the vessel or the bottom may be inclined or rough, I prefer to employ spreader means 75 consisting, as shown, of telescoping struts 31, 32, provided with means such as the set screws 33 to hold them in proper position. Such spreaders extend from each line to the adjacent line to hold 80 them thus spread in a pattern which previous survey has shown will fit a particular part of the vessel to which these lines are to be attached. The spreaders may either be secured to the lines 3 above their hooks 30, or extensions 34 may be 85 dropped from the corners of the spreader, but secured to the lines 3, these extensions 34 carrying the means to attach to the vessel. Obviously the pattern formed by the spreaders 31, 32 may be other than rectangular, as for instance, in attaching 90 to the bow or to the stern a triangular pattern may be preferable.

Connected to each buoy, and extending upward to the salvage vessel S, are air hoses generally designated by the numeral 4, and in particular 95 consisting of the hoses 41, 42, 43, 44, 45, 46 and 47, connecting to the respective buoys 22 to 27 inclusive. Air is supplied through these hoses from a suitable source of air under pressure, located upon the salvage vessel, and typified by the air 100 pressure tank 49. From this source air is conducted through suitable valve means, to be described later, to each one of the buoys, through the hose connected thereto, and in this way sufficient lifting effort is developed to raise the vessel. 105

The valve means referred to, whereby admission to and its discharge from the buoys 2 is regulated, is preferably concentrated all within 110 in a single casing 5, provided with a main valve

50 between it and the pressure supply tank 49, and having in the connection to the tank a quick detachable coupling means, indicated at 59. It is also provided with individual valves for the individual hose lines, these being indicated at 51, 52, 53, 55, 56, 57, etc. The individual hoses may likewise have gauges connected in their respective lines, such gauges being indicated at 65, 66 and 67 in Figure 6, connecting to the respective lines 10 45, 46 and 47.

The valve means is provided with a mounting arrangement, indicated at 58, to secure it upon the salvage vessel, but of such character that it can be quickly removed, and when thus removed, 15 the coupling 59 being released and the main valve 50 being closed, the entire casing may be thrown overboard, and is of such size and is provided with an air space whereby it will float, and will sustain the weight of the hoses and other lines attached 20 thereto, so that it may remain at the site of the operation while the salvage vessel seeks shelter, and can be picked up again when the weather enables resumption of operations.

The operation in general will be understood 25 from the drawings. Each buoy is partly or wholly filled with water, until it submerges, and is let down by a crane or derrick D upon the salvage vessel, spreader means 31, 32 having been secured to its lifting lines 3 in advance, if that is 30 found necessary. A diver then attaches the lifting lines to the vessel, and air is admitted through the hose 4 under pressure to expel the water from within the buoy 2 through the open neck 28. The buoy will shortly tend to float, and may be left 35 in this position, not exerting any great lifting effort, until all the buoys are attached, whereupon air is supplied to all of them simultaneously, or preliminarily to those which the survey has shown to require the greatest lifting effort, 40 until the vessel is raised free of the bottom, when the buoys will carry it up until they float at the surface.

It becomes obvious that it is desirable to know how much water has been forced out of each 45 buoy, or at least out of certain key buoys, and to that end I may provide float-controlled means in such buoys, connected to the salvage vessel by electrical or other suitable means, to indicate this level of the water.

50 Thus in Figure 8 there is shown a float 7 guided upon a rod 70 for vertical movement within the buoy, this float carrying a contact 71 movable along a guide 72, wherein are supported the several common contacts 73, and the individual contacts complementary thereto, designated 74, 75, 76 and 77. These contacts 74, 75, 76 and 77 may be connected through plugs 78 to suitable sockets 79 associated with the valve casing 5, and likewise associated with this valve casing are indicator 55 means, generally designated by the numeral 8, and consisting, for example, of the lights 84, 85, 86 and 87. These correspond to the respective contacts 74, 75, 76 and 77, and as they light up in turn, they indicate the level of the float 7 in the buoy to which they are connected. The electric leads connect to the respective buoys through conduits 80.

In the connection of the lifting lines, in the manner described, it is my preference that the 70 individual lines from each buoy be so spread that they will overlap lines of the next adjacent buoy;

in fact, I prefer that the line from each amidship buoy connect substantially at the same point as that to which is connected a lifting line of the next buoy but one. This is best illustrated in Figure 1, and by this arrangement, it 80 may be seen that the lifting effort is distributed and overlapped, thus effecting a sort of self-adjusting bridle arrangement whereby the buoys are maintained in their proper respective positions and later the stresses are so distributed that 85 the vessel is maintained properly upright.

The arrangement of lifting lines and their connection in the manner described is especially suitable to vessels which are partly buried in the bottom. There are occasions, however, when it is possible to pass a line beneath the vessel, such as indicated at 39 in Figures 4 and 5. Where this is feasible, it enables more of the buoys to be positioned about a vessel, and to be brought down close alongside, so that when the vessel is raised, 95 it will be raised higher in the water. The form of buoy used is preferable, since the restricted neck will prevent loss of air from the buoy, even though it may tilt and rock considerably, yet that type of buoy is not so well suited to be brought 100 down alongside a vessel, and to have the line 39 secured, as before, to the rings 29, because the exertion of the lifting effect will tend to tilt the buoy considerably and to twist the neck 28. To prevent this, I prefer that there be employed 105 spacing means to hold the buoy outwardly from the side of the vessel, these being indicated at 38 in Figures 4 and 5. The spaced means may take various forms, and may be secured to the neck, if desired, extending thereabout, but should 110 be of such character as to eliminate any tendency for the buoy to roll backward and forward along the side of the vessel, and I have therefore shown them as comprising spaced legs fitted at 115 their joints about the neck 28 of the buoy. 118 These would be fixed in position at the time of securing the line 39.

What I claim as my invention is:

1. Salvage apparatus comprising a buoy, a plurality of lifting lines secured to the bottom 120 of said buoy, and spreader means adjustable in length connecting the lower ends of the several lines to maintain them diverging in a predetermined pattern.

2. Salvage apparatus comprising a plurality of 125 submersible buoys normally open at the bottom, lifting lines extending from said buoys to points of securement to a vessel to be raised, a source of air under pressure, air hoses extending upward from each buoy, valve means including an individual valve for each hose to place such hose and its buoy in communication with the air pressure source, thereby to expel water from the buoy and to give it buoyance, and quick-detachable means to disconnect the valve means from the air pressure source, the valve means being floatable. 130 135

3. In salvage apparatus, a buoy having a depending restricted neck normally open to admit to its interior, lifting lines secured to its bottom and adapted for lifting engagement with a vessel 140 to be raised, close along the side thereof, means to supply air under pressure to expel water therefrom and to exert lifting effort, and means spacing the neck from the vessel's side, to permit the buoy to maintain an upright position. 145

EUGENE J. ROMANO.
